UNITED STATES PATENT OFFICE.

CHARLES MCVEETY, OF CHELTENHAM, PENNSYLVANIA.

COMBINED REGISTER BOX AND DEFLECTOR.

Application filed May 17, 1922. Serial No. 561,695.

To all whom it may concern:

Be it known that CHARLES MCVEETY, a citizen of the United States, residing at Cheltenham, in the county of Montgomery and State of Pennsylvania, has invented certain new and useful Improvements in a Combined Register Box and Deflector, of which the following is a specification.

My invention relates to a combined register box and air deflector.

The principal object of my invention is to provide a device of the class described, of an abundant free air capacity, to receive the returned air from the floor level and 15 to discharge the warm air from the heater, whereby a rapid circulation of air may be had in large volumes at a low temperature, in order to furnish an even degree of heat.

A further object of the invention is to 20 provide a device of the class described whereby the area of the floor openings may be greatly decreased.

A still further object is to provide a device of the class described that will discharge the warm air from a heater and receive the cool air from the floor levels of more than one room, as desired.

A still further object is to provide a device of the class described that may be installed in connection with a mantel, fire place, partition, artificial fire place having logs and electrical attachments, and other articles of furniture or ornamentation, thereby combining utility with beauty. The 30 demand in the modern home is for a more attractive and ornamental register than the floor gratings universally used and in consequence this present style of register box may be furnished in a wide variety of 35 pleasing forms and finishes and may be positioned in various parts of a room and in connection with various articles of furniture, or otherwise, exclusive of the floor levels.

For the purpose of illustrating my invention I have shown in the accompanying drawings the form thereof which is at present preferred by me, since the same has been found in practice to give satisfactory 45 results, although it is to be understood that various instrumentalities of which my invention consists can be variously arranged and organized and that my invention is not limited to the precise arrangement and organization of these instrumentalities as 50 herein shown and described.

In the drawings:—

Figure 1 is a diagrammatic perspective view of my assembled and connected device installed in a fire place under a mantel, 60 illustrating the method of receiving the returned air from the floor level of a room and the distribution and deflection of the ascending warm air from the heater;

Figure 2 is an end elevational view of 65 the positioning of the cool air return outlets shown in Fig. 1 on the opposite sides of a room partition in order to return the cool air from the floor level of two rooms simultaneously;

Figure 3 is a perspective view of my combined register box and deflector;

Figure 4 is a cross sectional view of the said register box and deflector;

Figure 5 is a vertical sectional view on 75 line 5—5 of Fig. 4;

Figure 6 is likewise a vertical sectional view, similar to Fig. 5, illustrating a modification of the device whereby the warm air ascending from the heater is deflected to 80 but one room; and

Figure 7 is a perspective view of the deflector.

Referring now in detail to the various figures of the drawing, wherein like parts are referred to by like reference numerals, 85 10 represents a heater, of a type used for hot air heating purposes and particularly for a recirculating system of hot air heating as embodied in Letters Patent #1,393, 90 301, issued to me October 11th, 1921, provided with an outer shell or casing 11, the conventional inner shell or radiator and an air thorofare or passageway therebetween, a base 12, a bonnet 13 and a main 95 hot air outlet pipe 14 to a first floor register. Laterally extending hot air outlet pipes 15 project from said bonnet 13 and are provided with the usual type of damper 16 to regulate the flow of hot air there- 100 through.

Cool air ducts 17 and 18, preferably rectangular in form, are provided, paralleling each side of the casing 11 and in spaced relation thereto, the lower portions thereof 105 having the connections 17' and 18' to openings in the base 12 of said heater 10 whereby cool air may be admitted to and circulate through said heater. The upper portions of the ducts 17 and 18 are adapted to receive like ducts 30 and 31 depending from the 110 register box 20.

A damper 19, is suitably mounted on a collar 13' connecting the bonnet 13 with the main outlet pipe 14, within said pipe 14, so that when closed said damper 19 acts as a closure or top to the bonnet 13.

My combined register box and air deflector comprises, substantially, a rectangular box 20, open at the top and having a rectangular opening 21, substantially, centrally, in the under side or base 22 thereof. In said opening 21 a pipe 23 is secured and projects downwardly therefrom at an angle and terminates in an annular portion 24 adapted to fit within the outlet pipe 14 from the heater 10. The angular portion of said pipe 23 at its apex is flattened on its four sides to conform to the rectangular form of the opening 21. In lieu of this construction a rectangular pipe 24', as in Fig. 6, may depend from the opening 21 and be secured directly to the bonnet 13 of the heater 10, eliminating the outlet pipe 14. In this instance the damper 19 would also be made in rectangular form instead of annular. Other suitable means may be employed to increase the area of the pipes 23 or 24' extending from the bonnet 13 in order that they may conform at their upper terminals to the form of opening 21 in the box 20.

Cool air deflectors 35—35 are secured to the base 22 of the box 20 adjacent the outer sides of the partitions 26—26 and are bent forwardly and secured to the upper inner portions of the ends of the box 20 adjacent the openings 28—28.

A rectangular opening is provided in the front of the box 20 for the positioning therein of a grille 37. This opening may be other than rectangular in form, if desired. A bar 38 is secured transversely of said opening, adjacent the top thereof and serves to divide the opening into two openings.

I have illustrated in Fig. 1 of the drawings the heater 10 with my register box and deflector connected thereto, placed in the basement or cellar of a dwelling house so that the register box is positioned in an open fire place, beneath a mantel. The same, however, may be positioned beneath a book-case, china-closet, or other article of furniture or ornamentation.

The said combined register box and deflector is illustrated in Figs. 1, 2, 4 and 5 of the drawings in position for distributing warm air to more than one room and to return the cool air from the floor levels of said rooms, while in Fig. 6 it is shown in position for distributing and deflecting warm air to but one room.

Describing the construction applicable to distributing warm air and returning cool air from more than one room, the device is positioned as shown in Fig. 1. Grilles 33 and 34 are positioned, as shown in Fig. 1, on either side of a room partition 43 and are

secured over the openings 28—28, the walls or subbase of the rooms being apertured for such purpose. I have shown the grilles 33 and 34 on one side only of the fireplace 41, but it will be understood that similar grilles may be employed on the opposite side of said fire place.

The said register box 20 is positioned so that the partition bisects an opening 28 in said box whereby the cool air from the floor levels of the rooms divided by said partition travels through the grilles 33 and 34 into the opening 28 and is returned to the heater 10 by means of the ducts 30 and 17 and is recirculated through said heater.

One of the openings 28 may be closed if it is desired to return the cool air from the rooms adjacent but one side of the fire place 41.

If required, an extension pipe 32 may be secured in the opening 28 and the grilles 33 and 34 be secured over the open outer end of said pipe 32.

The cool air ducts 30 and 31 are run between the joists 42, it being unnecessary with this device to cut out more joists than is necessary to install the register box 20.

A separable deflector, 39, triangular in form, adapted to fit within said box 20, between the ribs or cleats 25 and over the rectangular opening 21, is provided with a flat top portion 40, of less width than the top of said deflector 39, and overlaps each end of said top, the said overlapping portions resting upon the ledges 27—27 formed at the upper edges of the partitions 26—26. When it is desired to distribute warm air to more than one room the rear of the register box 20 is provided with an opening similar to the opening in the front thereof, communicating with a like opening in the opposite wall or partition, and a grille similar to the grille 37 is positioned thereover.

The warm air ascending through the opening 21 in the box 20 is deflected outwardly through the front and rear openings thereof by striking against the deflector 39 distributing the warm air to the two rooms. Said warm air on account of said deflector 39 cannot ascend vertically through said box 20. A strip or strips of asbestos, or other non-inflammable material, is secured to the upper portions of the deflector 39 on the front and rear thereof. The openings 28—28 in said box 20 are not closed at the top as the cool air deflectors 35—35 do not extend to the top of said openings and this provides for a circulation of air transversely of the box 20, the top of said box 20 being open between the top 40 of the deflector 39 and whatever objects rest upon the top of said box 20; there will also be a circulation of air through the front and rear openings in said box 20 above the transverse bars 38—38. This circulation is caused by the

inflow of air under the cool air deflectors, which induces air to flow in the top of the end openings over the deflector plates whereby whatever object rests upon the top of 5 the box 20 will be protected from the heat.

In the modification shown in Fig. 6 adapted for distributing warm air to but one room by means of the pipe 24' and the front opening, (the rear opening being 10 closed), the deflector 39' is positioned within the box 20 in a right triangular position so that the warm air is deflected in the one direction only, i. e., outwardly, through the front opening.

15 An extension pipe 32' may be secured to the front opening in the box 20 and the grille 37 secured over the open outer end of such pipe, if desired.

I do not restrict myself to the exact details of construction, combination and arrangement of parts herein set forth, it being obvious that minor variations thereof not involving the exercise of invention may be made by the skilled mechanic and such 20 parture from what is herein described and claimed, not involving invention, I consider as within the terms and scope of my herein-after appended claims.

I claim:—

30 1. A device of the character described, comprising a register box having openings in its base and ends, said base openings having communication with the heating chamber of a heater, deflector plates adapted to 35 guide cool air from the end openings to the base openings, the tops of said deflector plates being arranged below the tops of said end openings, a pipe depending from the register box and adapted to connect the register box with the warm air outlet of the heater, and a deflector arranged within the register box, having its sides converge towards the pipe connected with the heater, whereby air ascending from said heater will 40 be deflected from openings in the front and rear of the registry box, said deflector having its top arranged below the top of the register box thereby allowing free circulation 45 of cool air from the tops of the end openings.

50 2. A device of the character described, comprising a register box adapted to be arranged above the floor and having relatively large openings in its opposite ends, down-

wardly extending deflectors arranged within 55 the end portions of the register box adjacent to the end openings and serving to divide the end openings into upper and lower sections, the cool air travelling inwardly and downwardly through the lower opening sections 60 beneath the deflectors serving to induce air into the upper opening sections above the deflectors thereby maintaining the upper portion of the box suitably cool, depending 65 pipes leading from the deflectors to the heating chamber of the furnace, a pipe connecting the heating chamber of the furnace with the central portion of the register box, said box having hot air outlet openings in 70 its opposite sides arranged at substantially a right angle to the cool air inlet end openings, and a downwardly tapering deflector arranged within the central portions of the register box and disposed at substantially a right angle to the cool air deflectors, said 75 downwardly tapering deflector having upwardly diverging faces arranged opposite the hot air outlet openings.

3. A device of the character described, 80 comprising a register box adapted to be arranged above the floor and having relatively large openings in its opposite ends, 85 downwardly extending deflectors arranged within the end portions of the register box, adjacent to the end openings and serving to divide the end openings into upper and lower sections, the cool air travelling inwardly and downwardly through the lower opening sections beneath the deflectors serving 90 to induce air into the upper opening sections above the deflectors thereby maintaining the upper portion of the box suitably cool, depending pipes leading from the deflectors to the heating chamber of the furnace, a pipe connecting the heating chamber of the furnace with the central portion of the register box, said box having a hot air outlet opening in one of its sides arranged at substantially a right angle to the cool air inlet end openings, and a deflector 95 having a slanting face arranged opposite the hot air opening, and disposed at substantially a right angle to the cool air deflectors, whereby hot air is deflected through the 100 hot air opening into the room.

In testimony whereof I affix my signature.

CHARLES McVEETY.
